UNITED STATES PATENT OFFICE.

G MURL GORDEN, OF PORTLAND, OREGON, ASSIGNOR, BY MESNE ASSIGNMENTS, TO AMERICAN BY-PRODUCTS CORPORATION, A CORPORATION OF WASHINGTON.

MULTIPLE-UNIT RETORT.

Application filed November 22, 1921. Serial No. 516,996.

To all whom it may concern:

Be it known that I, G MURL GORDEN, a citizen of the United States, and a resident of the city of Portland, county of Multnomah, and State of Oregon, have invented a new and useful Improvement in Multiple-Unit Retorts, of which the following is a specification.

This invention relates to the separation of volatile products from solid carbonaceous material such as shale, coal, saw-dust or waste products, by heating the same in retorts and conveying the evolved vapors to a condensing system.

In prior systems the distillation was done with one graduated heat, while in my new improved method I have retorts with different heats which volatilize each family of products in separate retorts.

The object of this invention is to provide an improved method and apparatus which will overcome the objectionable features of volatilizing these carbonaceous materials by a continuous process. When the materials are brought up from ordinary heat to the heat necessary to vaporize the least volatile substance the intermediate stages produce a certain gummy mass in the retort. This handicaps highly efficient and ready vaporizing because the mass does not present a sufficient open surface to the heat. By vaporizing the light, medium and heavy fuels separately we pass these critical temperatures hurriedly and overcome the evil influences of this partial vaporization. The three distinct classes of products which volatilize from these carbonaceous materials are the light, or for example gasoline, kerosene; the medium, or lubricating oils; and the heavy, the paraffins and waxes.

The products which are not volatilized and remain in the retorts in the form of residue are not taken into consideration.

In the accompanying drawings—

Fig. 1 shows the part of my retorting apparatus which includes the hopper, the pre-heating chamber and the first and second retorts which drive off the more volatile matters.

Fig. 2 is a side view of the remainder of my apparatus shown in Fig. 1, and includes

the third retort, condensers, and sources of steam, power and heat. If Fig. 2 is placed alongside of Fig. 1 and the lines superimpose one another, a correct idea can be obtained of the complete assembly.

Fig. 3 is a cross sectional view of the end of one of the retorts and shows the manner of conveying the material in the retorts and the means of passing the material from one retort to the next.

Fig. 4 is a cross sectional view taken on the line 4—4 of Fig. 3, and shows the means for agitating the material in the retort so as to prevent a gummy mass from forming on the bottom and thereby prevent thorough retorting.

The description of my apparatus by which I attain my object is as follows: Shale, or whatever carbonaceous material used, is broken up into pieces that would readily sieve through one-quarter mesh and is dumped in the hopper *a*. It then passes through a preheating chamber *b* which dries and prepares the material. This preheating chamber is heated by steam coils which are passed around it. The dried material then passes from this preheating chamber to a hopper *c* from which it is conveyed by an auger like conveyor *d* to the first retort *e*. This retort is heated to a fixed temperature which will volatilize all of the light family of products. In it revolves another spiral conveyor *v* to which are attached buckets *w* which agitate the material so that it presents an even depth throughout the retort and expedites thorough volatilization. This conveyor revolves at a fixed speed and allows the material a certain length of time to pass through this retort. At the end is another hopper *f* through which the shale drops to a spiral conveyor *g* which passes it along to the second retort *h*. These intermediate conveyors are of a relatively small diameter and therefore, work at an increased speed.

The action of the shale coming down from the retort fills them to capacity and thus makes an air seal which prevents the heat of the retorts from passing back into the previous or lower heated retort. The material in this second retort *h* is then subjected to a higher heat which drives off the medium

family of products which constitute the lubricants. As in all the retorts, this vapor is conducted through vertical tubes at the top to appropriate tubes which convey this vapor to a condenser. In the accompanying diagrams the vertical tubes shown as e^3 , h^3 and k^3 have adjustable baffle plates α which prevent the solid material, such as dust, from passing through the tubes and into the condenser where they would tend to clog the system.

The shale then passes from this retort through a similar hopper i and conveyor j to the third retort k where like treatment drives off the heavy waxes and paraffins. The residue then passes out through a hopper l and the spiral conveyor m to another conveyor n where this residue is passed to the slag pile.

As indicated before, the vapor driven off rises through the vertical tubes e^3 , h^3 and k^3 to the vapor chamber e' , h' and k' through the conveying tubes e^2 , h^2 and k^2 to a suitable condenser indicated as o . There the vapor is liquified and is drained off. Part of the vapor driven off will not condense and this gas is allowed to pass from the top of the condenser through pipes indicated as o' to a vacuum pump p . The action of this vacuum pump not only draws the gas from the condenser but also tends to create a region of low pressure in all of the conveying tubes from the retorts and thus expedites the conveying away of these vapors so that scorching and combustion will be prevented.

The gas from the vacuum pump is delivered to a gas storage tank q from where it passes through suitable pipes r which connect with the exterior burners r' , r^2 , and r^3 which heat the separate retorts. These gas pipes are all equipped with valves which regulate the pressure and thus allow the temperature in the retorts to be regulated.

The exterior gas flame is one source of heat to the retorts. Another source of heat is coiled sections t^5 of pipe which contain super heated steam, which is received thru a main pipe t and branch pipes t' , t^2 , and t^3 and which is provided by steam boiler s . This steam coil passes through a hollow cylinder u and is blown off at the end. No steam passes into the vaporizing chambers but the heat is merely heat of radiation from the hollow cylinder u .

My manner of providing two separate sources of heat allows for more even distribution and closer adjustment.

The heat of the steam can be also regulated by suitable valves and the pressure reduced or raised to the conditions required.

The illustrations and description above given are merely intended to show a practical mode of construction of my device. The particular details of construction above de-

scribed are however, variable to suit the ideas of manufacture providing such variation retains the essential features of my invention.

I claim:

1. A distilling apparatus of the character described comprising a plurality of horizontally arranged retorts which are heated independently of each other with the ends of the retorts spaced and in step down formation, a horizontal cylindrical passage way connecting two adjacent retorts, a hopper for the passage way communicating with the preceding retort, the passage way being smaller in diameter than the retorts, a spiral screw operable in said passage way and underlying the hopper and adapted to convey material out of one retort into the other, the said spiral screw being of substantially the same diameter as the passage way and thus adapted to provide a heat seal between the retorts. 70

2. A distilling apparatus of the character described comprising a plurality of horizontally arranged retorts which are heated independently of each other with the ends of the retorts spaced and in step down formation, means in each retort for passing material thru the retort at a fixed rate of speed, a horizontal passage way connecting two adjacent retorts, a hopper for the passage way communicating with the preceding retort, a spiral screw operable in said passage way adapted to convey material out of one retort into the other, a vapor chamber mounted on each retort and connected therewith by a plurality of passage ways, and baffle plates arranged in said passage ways thereby to prevent solid matter from passing into said vapor chambers. 100

3. A distilling apparatus of the character described comprising a plurality of horizontally arranged retorts which are heated independently of each other, and a plurality of heating means, one of said means including a steam coil extending longitudinally and axially of the retorts and the other heating means being located beneath the retort and spaced therefrom. 110

4. A distilling apparatus of the character described comprising a plurality of horizontally arranged retorts which are heated independently of each other, a spiral screw in each retort for passing material thru the retort at a fixed rate of speed, a passage way connecting two adjacent retorts, a spiral screw operable in said passage way adapted to convey material out of one retort into the other, a vapor chamber mounted on each retort extending substantially the entire length of the retort and connected therewith by a plurality of passage ways. 115

5. A distilling apparatus of the character described comprising a plurality of horizontally arranged retorts which are heated 130

independently of each other, a spiral screw retort extending substantially the entire length of the retort and connected therewith the retort at a fixed rate of speed, a passage way connecting two adjacent retorts, a spiral screw operable in said passage way adapted to convey material out of one retort into the other, a vapor chamber mounted on each

length of the retort and connected therewith by a plurality of passage ways, and baffle plates arranged in said passage ways there-

to prevent solid matter from passing into said vapor chambers.

G MURL GORDEN.
